UNITED STATES PATENT OFFICE.

FREDERICK E. SMALL, OF KANSAS CITY, MISSOURI.

ORE-CONCENTRATING MACHINE.

1,314,371.

Specification of Letters Patent. Patented Aug. 26, 1919.

Application filed January 27, 1919. Serial No. 273,253.

To all whom it may concern:

Be it known that I, FREDERICK E. SMALL, a citizen of the United States, residing at Kansas City, in the county of Jackson and 5 State of Missouri, have invented a new and useful Ore-Concentrating Machine, of which the following is a specification.

My invention relates to ore concentrating machines which are employed in separating mineral grains from their ores and 10 particularly to an apparatus of this character which may use either dead or flowing water, and the object of my invention is to provide a simple, economical, and efficient 15 separator having facility for effecting violent and antagonistic concussions of the water used by the separator and for trapping froth and slime and saturating the same, also, to provide the separator with a 20 peculiar concentrating table having facility for cleaning concentrates received thereon.

I attain these objects and other advantages by means of the mechanism and combination of parts illustrated in the accompanying drawing in which—

Figure 1, is a side elevation of the separator, partly sectioned, embodying my invention.

Fig. 2, is a rear elevation of the same, the 30 endless sprocket chain being omitted.

Fig. 3, is a front elevation of the same, and showing the means for guiding the separator in oblique direction and the scalloped wheels for jarring the machine.

Fig. 4, is a top plan view of the tank proper, and showing the self-cleaning concentrating table in the floor of the tank, a 35 part of my invention.

Fig. 5, is a transverse section through the tank, substantially on the line V—V, on 40 Fig. 4, and showing the rotary gate for regulating the discharge of concentrates from the concentrating table, a part of my invention.

Fig. 6, is a transverse section through the concentrating table, on the line VI—VI, on 45 Fig. 4.

Fig. 7, is a top plan view of a fragment of the carrier member and supporting 50 medium, and showing the pivoted guide for

deflecting the tank in oblique direction, a part of my invention, and

Fig. 8, is a perspective view from the lower side of the froth and slime trap, a 55 part of my invention.

Similar numerals of reference refer to corresponding parts throughout the several views.

Referring to the drawing—the concrete emplacement 1, the metal sills 2, the metal 60 cross sills 3, secured on the emplacement, constitute the supporting medium for the separator mechanism hereinafter described.

Scalloped wheels 4, are revolvably mounted in bearing boxes 5, the latter being disposed oppositely in pairs and secured on the sills 2. Corrugated plates 6, is secured 65 on one of the sills 2, at an intermediate point thereon between the bearing boxes 5. A vertically extending pivot bearing 7, is secured 70 on the forward cross sill 3, so that it will be disposed closely adjacent to one of the sills 2, and is provided with a bore 8, of a suitable depth to loosely receive the pivot member hereinafter described. A hori-

zontally disposed carrier member 9, which 75 may be either of wood or metal, preferably metal, and substantially as wide as the supporting members and long enough to allow its end portions to project a little 80 distance beyond the ends of the supporting medium, when the former is reciprocated horizontally forward and rearward a distance of 2 or 3 inches, more or less, is provided to convey a concentrator hereinafter 85 described. A segmental wheel 10, is rotatably mounted on the lower side of the carrier, at one side thereof, and directly over the corrugated plate 6, and is provided with

cogs or teeth 11 which are adapted to loosely 90 engage the corrugations on the plate 6. A coupler 12, is secured on the front end of the carrier and a link 13, is connected by a pin 14, with a coupler, in such a manner that the link may turn thereon. A pivot 15, is 95 formed integral with the link 13, and at right angles thereto, and is adapted to loosely enter the bore 8, in the bearing 7, and turn therein. A coupler 16, is mounted on the rear

end of the carrier and a connecting rod 17, is 100

movably connected therewith by a pin 18, which is extended loosely through the rod and coupler in the well known manner, the outer end of the rod is connected 5 with a crank 19, which is mounted on a driving wheel 20, on a drive shaft 21, the latter being driven by any suitable power. An elongated tank 22, is secured on the carrier 9, and is adapted to be carried thereby. The 10 tank is provided with a bottom portion 23, which is dimensioned in length and width, substantially the same as the carrier, and is provided with upwardly curved integral reduced end portions 24 and 25, the former 15 of which terminates at the upper edges of the sides 26, of the tank and forms the receiving end thereof, and the latter terminates a little distance below the upper edges of the sides of the tank and, thereby, provides 20 a discharge passage 27, for the discharge of tailings. The bottom portion 23 of the tank is recessed longitudinally, from the point of departure of the curved portion 24, to substantially the middle of the tank, 25 in which recess a hollow corrugated table 28, provided with a series of inclined parallel ridges 29, is entered. The upper ends of the ridges 29, register with the inner end of the curved portion 24. The corrugations or 30 ridges 29, are formed to slope downwardly, thereby forming valleys 30. The table 28, is provided with an integral head 31 and a foot plate 32, the latter having a vertical face portion 33, extending from its upper 35 edge downwardly a little distance and then formed concaved, thereby forming with the head 31, non-communicating chambers 34 beneath the ridges. Openings 35, are made in the foot plate, at the ends of the valleys 40 30, for the purpose of discharging therethrough the concentrates which shall accumulate therein. Nipples 36, are extended through the head 31 and communicate with the chambers 34, and with air pipe 39, the latter 45 communicating with a source of compressed air, not shown, thereby air under pressure is admitted to the chambers 34, and vented therefrom, through orifices 40, across the valleys 30, in this instance, at a little 50 angle, and against the slopes of the ridges 29. A gate 41, is rotatably mounted in the sides of the tank and is adapted for opening and closing the discharge openings at the lower ends of the valleys 30, said gate comprises 55 a rotatable shaft 42, having radial arms 43, carrying a convexed plate 44, which is designed and adapted to be closely adjusted with the concaved portion of the foot plate 32, for the purpose of being rotated to regulate the discharge of concentrates 60 from the concentrating table 28, through openings 35, at the lower ends of the valleys 30. A handle 45, is secured on the outer end of the shaft 42, for conveniently oper-

ating the gate. Down spouts 46, are secured on the carrier, and their upper ends are adapted for receiving discharges of concentrates and solution from the valleys 30, in the concentrating table and their lower ends communicate with a receptacle or trough 47, 70 on or in the emplacement 1. The inner side of the tank bottom portion 23, is inclined upwardly to register with the inner end of the curved reduced portion 25. A bridging member 48, is demountably mounted on the 75 upper edges of the tank and forms a span across the same. The member 48 comprises a platform 49, which is provided on its lower side with a series of spaced apart curved depending plates 50, which are 80 adapted for extending crosswise the inner precincts of the tank and are provided with a depth a little greater than one half the depth of the tank, so that they may penetrate the water in the tank and thereby form 85 compartments 51, for receiving and trapping froth and slimes which may be carried by the solution in the tank during the separating or concentrating process. The concaved sides of the plates 50, are, preferably, 90 presented to the receiving end of the tank, so that the foremost of the plates will be better adapted to arrest froth and slimes in the case of running solutions from auxiliary separators delivered to the tank 22, for completion of the process of concentrating mineral grains. Spaced apart sprocket wheels 52, are revolvably mounted in the tank, on which an endless sprocket chain 53, is operatively mounted, the endless chain being 100 provided with transverse plates 54, which are projected outwardly of the chain and adapted for dragging the tailings from the tank and discharging the same at the opening or passage 27. A pulley 55, is mounted 105 on the rearward sprocket wheel shaft and provides opportunity for the drive shaft to drive the sprocket wheels, by means of a belt, not shown, mounted on the pulley 55, and a pulley on the drive shaft, not shown. 110 A belt tightener 56, is mounted on the side of the tank and is adapted for depressing the sprocket chain in the tank, so that the plates 54 shall operate along the floor of the tank proper, or at any point adjacent 115 the floor.

The separator embodying my invention and organized in the manner hereinabove described operates as follows: If inert or dead water is employed the gate 41, is rotated to close the openings 35, at the ends of the valleys 30, and the tank is then filled with water, preferably, to a depth of two thirds of its capacity, and the ore particles fed therein. A driving power is then applied to the driving wheel 20, and it in turn imparts a reciprocating motion to the carrier member 9, by means of the connecting

rod 17, thereby imparting a forward and backward motion to the tank and effecting a disturbance of the solution in the tank, because of the lag in overcoming the inertia 5 of the solution. When the carrier is reciprocated, it carries on the scalloped wheels 4, and on the teeth or cogs thereof, and thereby the carrier is vibrated with great frequency in vertical direction, producing at each vibration a violent jar or shock to the solution in the tank, thereby materially assisting in the process for liberating the mineral grains from the ore particles. When the carrier moves, the segmental cog wheel 10, is forced to rock in the corrugated plate 6, so that in each forward and backward movement of the carrier, the latter will be tilted upwardly, at one side, whenever the segmental wheel shall 10 pass its center. When the carrier is reciprocated, the guide bar 13, is forced to rotate in its rotative field and the end of the carrier is thereby swayed laterally, imparting to the solution in the tank a substantially 15 swirling motion and similar to the well known miner's pan motion. The above described motions and vibrations subject the solution to violent and frequent antagonistic shocks and concussions, thereby effecting 20 complete saturation of the ore particles and segregation of the mineral grains carried thereby, the latter being provided opportunity to gravitate to and find repose in the 25 valleys 30, in the concentrating table. When 30 the segregated mineral grains pass into the valleys 30, air under pressure is vented from the chambers 34, through the orifices 40, and directed across the valleys in upwardly ascending opposed jets which 35 counter the mineral grains and effects a separation therefrom of all light waste substances, such as sand, silt, and the like, thereby clean concentrates occupy the valleys, the waste substances being carried in 40 solution, or deposited on the floor proper of the tank. It is my experience the wet process for concentrating mineral ores produces quantities of froth and slime, both of which carry mineral grains which are lost or wasted 45 with the tailings, because provision was not made for saturating the same to allow the mineral grains to be segregated. Froth and slime are, by my invention, trapped in compartments 51, of the bridging member 48, 50 and therein subjected to the shocks and vibrations set up by the devices herein-above mentioned, which shock and concussion acting on the froth and slime in the narrow compartments of the bridging member effects 55 complete saturation of the same and allow the mineral grains to be segregated. The curvature of the plates 50, induces the mineral grains to slip down the concaved surface of the plates and gravitate there-

from into the valleys 30. At the time the 65 carrier is reciprocated the sprocket wheels 52, and the sprocket chain 53, thereon, are driven by a belt, not shown, connected between the pulley 55, and a pulley, not shown, on the shaft 21, and in such a manner that 70 the drag plates 54, shall move from the receiving end of the tank to the discharge end thereof. The belt tightener 56, is adjusted to the sprocket chain to depress the same, so that the plates 54, may drag along 75 and over the concentrating table and the floor proper of the tank and, thereby, engage and drag the tailings and discharge the same from the tank at the discharge passage therein. When it is desired to remove 80 the concentrates the gate 41, is rotated to open the ends of the valleys, whereupon the concentrates will gravitate into the down spouts 46, and into a receptacle there below. When the separator is employed to 85 complete the process started by an auxiliary separator, the gate 41 is left open to any suitable degree and allowed to remain open, so that concentrates may gravitate from the valleys continuously. The extent of the 90 opening of the gate depends on the capacity of the auxiliary separator, the larger run of solution requiring the greater opening, and vice versa. The separator constructed and operated as I have described requires 95 small space and provides great capacity for ore tonnage.

Having described my invention what I claim is—

1. In an ore concentrator, the combination 100 of a wedge-shaped table forming substantially one half of the floor thereof and having V-shaped valleys extending longitudinally of the concentrator and inverted V-shaped non communicating chamber separating the valleys and adapted for venting compressed air across the latter, down spouts arranged in the floor of the concentrator at the inner ends of the valleys in said table and adapted for receiving the 105 flow of concentrates from the valleys, and a gate rotatably mounted in the floor of the concentrator and arranged to simultaneously dam the valleys in said table and prevent the flow of concentrates from said table to 110 said down spouts.

2. In an ore concentrator, the combination 120 of a wedge-shaped table forming substantially one half of the floor thereof and having V-shaped valleys extending longitudinally of the concentrator and inverted V-shaped non communicating chambers separating the valleys and adapted for venting compressed air across the latter, down spouts arranged in the floor of the concentrator at 125 the inner ends of the valleys in said table and adapted for receiving the flow of concentrates from the valleys, a gate rotatably

mounted in the floor of the concentrator and arranged to simultaneously dam the valleys in said table and prevent the flow of concentrates therefrom to said down spouts, and
5 a bridging member mounted on the upper side of the concentrator and provided on its lower side with spaced apart depending curved plates extending transversely of the interior of the concentrator and forming
10 compartments adapted and arranged for

trapping the slime carried by the solution in the concentrator when the latter is operating.

Dated, Kansas City, Missouri, January 24th, 1919.
